(57) CLAIM

The ornamental design for automobile starter clips as shown and described.

DESCRIPTION

FIG. 1 is a bottom, front and right side perspective view of automobile starter clips showing my new design;
FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 8.

The broken lines in the drawings illustrate portions of the automobile starter clips which form no part of the claimed design. Portions of the automobile starter clips are broken away to indicate that no particular length is claimed.
